OF PENNSYLVANIA.

BUNSEN BURNER.

1,157,734.

Specification of Letters Patent.

Patented Oct. 26, 1915.

Continuation in part of application Serial No. 811,314, filed January 10, 1914. This application filed May 14, 1914. Serial No. 838,461.

To all whom it may concern:

Be it known that we, LOUIS J. STRAUSE and OTTO SPAHR, both citizens of the United States, and residents of Philadelphia, county 5 of Philadelphia, and State of Pennsylvania, have invented certain new and useful Improvements in Bunsen Burners, of which the following is a specification.

Our invention relates to Bunsen burners 10 of the type particularly adapted for use in connection with gas stoves, incandescent gas lamps, self heating gas irons and the like and has for its object to construct such burners in a manner to protect the customary 15 flexible or other fuel conducting tube from the injurious effects of the heat generated in the element with which said tube is operatively connected.

Our invention will be fully described 20 hereinafter and the features of novelty will be pointed out in the appended claims.

The present application is in part a division 25 of one filed by us in the United States Patent Office on January 10, 1914, Serial No. 811,314.

Reference is to be had to the accompanying drawings illustrating certain examples of our invention and in which—

Figures 1, 2 and 3 are longitudinal sections 30 of different forms of our improvement; Figs. 4 and 5 are similar views of two further forms of our improved air hood; Fig. 6 is an end view of Fig. 4 and Fig. 7 is a sectional view on the line 7—7 of Fig. 5.

In the form shown in Fig. 1 of the drawings, 35 10 represents an air hood which may be of any suitable or desired construction and material and as illustrated is externally screw-threaded to accommodate an air regulating shutter 11 of any desired type adapted to coöperate with the usual air inlets 12 for regulating the admission of air to said air hood for admixture with the gaseous fuel in the customary manner. The said air-hood 10 is further internally screw-threaded 40 at one end to receive the reduced externally screw-threaded neck 13 of the nipple 14. In this form of our improvement the said nipple 14 is constructed of a material which

50 is a poor conductor or a non-conductor of heat and is provided with a central passage 15 terminating in an enlarged chamber 16 which is internally screw-threaded to receive the screw-threaded neck 17 of the

nozzle 18. The latter is thus carried by said 55 nipple and may be made readily accessible, when this is desired for any purpose, by simply unscrewing the nipple 14 from the air-hood 10. The said air-hood 10 may be detachably connected with the burner tube 60 of a gas-stove, gas lamp, gas-iron or the like in any customary manner as by internally screw-threading as indicated at 19 and the one end of the usual flexible or other tube 20 for supplying the fuel may be 65 slipped over the said nipple 14 for instance as clearly shown in Fig. 1. In this form the air-hood 10 and connected parts as well as the nozzle 18 may be constructed of metal, while, as above stated the nipple 14 is made 70 of a material which is a poor conductor or a non-conductor of heat. With ordinary constructions the heat from the burner is conducted along the various metallic tubes or other parts included in the device and by 75 coming into contact with the said fuel tube 20, which is usually constructed of rubber or a combination of rubber and some other substance, vulcanizes the said tube upon the nipple and thus prevents its removal therefrom without fracturing or otherwise injuring the said tube, and in structures where the fuel supply tube is attached in a manner other than by slipping over a nipple is conducted to said tube and injures or destroys 80 85 the same. The life of the tube in such constructions is in consequence materially reduced and the same is oftentimes rendered leaky and dangerous to use. In the present construction so far described the above objections are absolutely overcome and the said tube is effectively insulated against the effects of said heat by the nipple 14 of insulating material which arrests conduction of heat and prevents the same from injuring 90 95 the tube 20.

As shown in Fig. 2 of the drawings the arrangement is reversed as it were, the air-hood 10^a in this form being constructed of a material which is a poor conductor or a 100 non-conductor of heat, while the nipple 14^a may be made of metal. In this form the medium for connecting the fuel supply tube with the air hood may be other than a nipple. Otherwise this second form may 105 be constructed and operated the same as the form first described, the difference being that in said second form the air-hood acts

as a medium for arresting the conduction of heat before the tube 20 is reached.

In the form illustrated in Fig. 3 the air-hood 10^b and nipple 14^b are both constructed 5 of a material which is a poor conductor or a non-conductor of heat, while the nozzle 18 as in the previous forms may be of metal or other suitable material. With this last arrangement, which otherwise may be the 10 same and operate the same as the two forms previously described, both the air-hood and nipple serve to prevent the heat from reaching the tube 20.

In Figs. 3, 4 and 6 the air-hood 10^b and 15 10^c of non-conducting material may be reinforced at one end with a metallic internally screw-threaded ring 21 suitably secured in position and adapted to receive the reduced screw-threaded neck of either of 20 the nipples 14, 14^a or 14^b.

In Figs. 5 and 7 the air-hood 10^a is also constructed of a non-conducting material and is inclosed in a metallic protecting sleeve or shell 22, said air-hood 10^a also being 25 adapted for connection with either of the nipples 14, 14^a or 14^b, the said protecting sleeve 22 being also illustrated in connection with the air-hood 10^b of Fig. 3.

In the two last forms, as in Figs. 2 and 30 3 the air-hood insulates the tube 20 against the effects of the heat generated by the burner, as will be readily apparent. It will of course be understood that, the air-hoods 10^b, 10^c and 10^a may be provided with suitable air regulating shutters adapted to co-operate with the air inlets 12 in the usual manner.

It will be seen that all forms of our improvements provide for the absolute protection 40 of the fuel supply tube against the effects of heat generated at the burner and conducted away therefrom by metallic or other parts of the device with which the tube is connected.

45 It will of course be understood that in all forms of our invention, the heat insulating means may be constructed of any material suitable for the intended purposes, although a substantially rigid fibrous material such as asbestos, wood or similar substances is preferred, and also that said means may be combined or included in Bunsen burners or 50

the like of different constructions from those shown.

Various changes in the specific forms 55 shown and described may be made within the scope of the claims without departing from the spirit of our invention.

We claim:—

1. A Bunsen burner of the kind described 60 comprising an air hood, a nipple having its inner end detachably secured in an end of said air hood, one of said elements being constructed of heat insulating material and a nozzle carried by the inner end of said 65 nipple and located within said air hood.

2. A Bunsen burner of the kind described comprising an air hood, a nipple of heat insulating material having its inner end screwed into an end of said air hood and a 70 nozzle carried by the inner end of said nipple and located within said air hood.

3. A Bunsen burner of the kind described comprising an air hood of heat insulating material, a nipple having its inner end 75 screwed into an end of said air hood and a nozzle carried by the inner end of said nipple and located within said air hood.

4. A Bunsen burner of the kind described comprising an air hood of heat insulating 80 material, a nipple of heat insulating material having its inner end screwed into an end of the said air hood and a metallic nozzle detachably secured to the inner end of said nipple and located within said air hood. 85

5. A Bunsen burner of the kind described comprising an air hood of heat insulating material, a metallic reinforcing sleeve surrounding said air hood, an internally screw-threaded metallic ring secured within an 90 end of said air hood, a nipple having a reduced end adapted to screw into said metallic ring and a nozzle projecting from the reduced end of said nipple and located within 95 said air hood.

In testimony whereof, we have hereunto set our hands in the presence of two subscribing witnesses.

LOUIS J. STRAUSE.
OTTO SPAHR.
